UNITED STATES PATENT OFFICE

CHARLES WAINWRIGHT, OF ERIE, PENNSYLVANIA

SPEED AND PRESSURE GOVERNOR

Application filed July 29, 1924. Serial No. 728,928.

One object of my said invention is the provision of a steam driven compressor in which the thermal working conditions are improved and a high ratio of expansion and maximum efficiency are attained.

Another object is the provision of a steam driven compressor embodying improved and highly efficient automatic governing means.

Another object is the provision of a steam driven compressor of general high efficiency.

Another object is the provision of a steam cylinder of high efficiency characterized by a steam valve that is automatically always tight, by means whereby an extremely short cut off can be brought about without condensation due to highly efficient insulating means, by compression valves that afford constant compression irrespective of the point of cut off and by automatic means of high efficiency for controlling the cut off.

Other objects and practical advantages of the invention will be understood from the following description and claims when the same are read in connection with the drawings, accompanying and forming part of this specification, in which:

Figure 1 is a side elevation showing a steam driven compressor constituting one embodiment of my invention.

Figure 2 is an enlarged view, partly in elevation and partly in section, illustrating the preferred type of governor employed in the compressor.

Figure 3 is a vertical section of the governor at right angles to Figure 4.

Figure 4 is an enlarged detail view of the connections to the safety valve 30.

Similar numerals designate corresponding parts throughout the several views.

The engine to which my invention is shown applied includes the usual steam cylinder 1 which contains the usual piston whose operation is controlled by a steam valve.

The valve gear of the engine includes a block 21 in a link 22, and a connection between the said block 21 and the steam valve comprises a rod 23, Figures 1 and 2. The rod 23 is connected in turn, by a rod 24 with the vertically swinging arm 25 of my novel governor which is of the fly ball type as clearly

shown in Figures 1, 2 and 3. By reference to said figures it will be understood that when the governor is in operation the arm 25 is raised and lowered by centrifugal action, the said raising and lowering of the arm 25 being attended by raising and lowering of the link block 21 which determines the cut off of the steam valve. In addition to the elements referred to, the governor comprises a piston 26 connected by a link 27 with the arm 25, the said piston 26 being disposed in a cylinder 28 to which is connected a pipe 29 for the control of the piston by the air pressure of the compressor 30^a which is arranged in tandem with the cylinder as shown in Figure 1. From this it follows that when a predetermined air pressure is reached, said pressure will operate against the piston 26 to raise the arm 25 and thereby raise the link block 21 and slow down the compressor. As the pressure builds up the arm 25 will be raised by the raising of the piston 26 and the speed of the apparatus will be proportionately decreased. At 30 the governor is equipped with a safety valve, Figures 2 and 3, so constructed and arranged that in the event the driving connection, preferably belt or chain 50, of the governor is broken, live steam pressure will be utilized to raise the piston 26 and the link block 21 and thereby slow down the apparatus. In this connection it will be apparent that the safety valve 30 is provided with a conduit 30^a for the supply of steam thereto, and that the belt or chain 50 is connected with the safety valve in the manner best shown in Figure 4; also, that the valve 30 depends on the governor, said valve being connected to the steam line of the compressor and being closed when in its horizontal position. Should the belt 50 part the valve 30 because of the gravitation of its weight 30^a will be operated so as to permit steam to pass to pipe 29 when the steam pressure will cause the piston 26 to move upward and the governor to slow down and stop the compressor. In this connection it will be noted that the belt 50 when normally operating has one of its stretches in engagement with a gravitational lever 30^a connected with the weighted portion of the valve 30 as shown in Figures 100

4 and 5, and that gravitation of said lever 30° will be attended by release and gravitation of the said weighted portion of the valve.

The lever 30° is equipped with wheels 30^d above and below the rubber stretch of the belt 50, and hence said lever will be maintained in the position shown in Figure 4, so long as the belt 50 is intact, but when the belt breaks the lever 30° will gravitate—i. e., 10 swing downwardly and disengage its flange 30^c from the lateral upper portion of the arm 30^a on the weighted portion of valve 30, thereby permitting downward movement of said weighted portion to establish the supply of 15 steam to the pipe 29 and cylinder 28 and bring about stoppage of the compressor.

The steam inlet and the main exhaust for steam are designated by legends in Figure 2, and by comparison of Figures 2, 3 and 7 it 20 will be understood that steam passes from the inlet about the piston cylinder and past the steam valve to the interior of the cylinder, and from the cylinder the exhaust steam is carried past the steam valve to the chambers in the head (see upper arrow at right of Figure 3) and from said chambers the exhaust steam passes out through the main exhaust designated in Figure 2.

Having described my invention, what I 30 claim and desire to secure by Letters-Patent, is:—

1. In combination, a centrifugal governor, driving means therefor including a steam engine and a belt, an arm connected with the 35 governor, a piston connected with said arm, a steam valve complementary to said engine, a valve gear including a block connected with said steam valve and also connected with said arm, a cylinder containing said piston, a 40 normally-closed valve adapted to be connected with a source of steam supply and said cylinder and having a weighted portion; said valve having on its weighted portion a rod with a lateral portion, and a gravitational lever having means engaging one 45 stretch of the belt and also having a flange normally supporting said rod and movable by gravitation of the lever out of engagement with the rod.

50 2. In combination, a centrifugal governor, driving means therefor including a steam engine and a belt, an arm connected with the governor, a piston connected with said arm, a steam valve complementary to said engine, 55 a valve gear including a block connected with said steam valve and also connected with said arm, a cylinder containing said piston, a normally-closed valve adapted to be connected with a source of steam supply and said cylinder, gravitational means normally held by the belt against downward movement, and means for bringing about opening of the 60 valve on downward movement of said gravitational means following breakage of the 65 belt.

3. In combination, a governor, driving means therefor including a steam engine and a driving connection, a steam valve complementary to the engine and connected with and controlled by the governor, a piston connected with the governor, a cylinder containing said piston, a normally-closed valve adapted to be connected with said cylinder and a source of steam supply, and means operable by mishap to the driving connection to the governor for opening said valve and supplying steam to said cylinder.

In testimony whereof I affix my signature.

CHARLES WAINWRIGHT.
